No. 856,715.

PATENTED JUNE 11, 1907.

M. C. MATTHEWS.
TRAMWAY SWITCH.
APPLICATION FILED NOV. 10, 1906.

UNITED STATES PATENT OFFICE.

MALCOLM C. MATTHEWS, OF CHICAGO, ILLINOIS.

TRAMWAY-SWITCH.

No. 856,715.

Specification of Letters Patent.

Patented June 11, 1907.

Application filed November 10, 1906. Serial No. 342,889.

To all whom it may concern:

Be it known that I, MALCOLM C. MATTHEWS, a citizen of the United States, residing at Chicago, in the county of Cook and State of Illinois, have invented certain new and useful improvements in Tramway-Switches, of which the following is a specification.

This invention relates to new and useful improvements in tramway switches and it particularly pertains to a partially rotatable switch carrying diverging track sections.

It is a primary object of the invention to provide a switch of the above type embodying among its novel features of construction improved means for locking said switch in any position in which it has been set against accidental displacement and means for restricting the rotation of said switch at selected points in either direction.

The detailed construction will appear in the course of the following description in which reference is had to the accompanying drawings forming a part of this specification, like numerals designating like parts throughout the several views, wherein

Figure 1 is a top plan view of a switch constructed in accordance with my invention. Fig. 2 is a side elevation of a device provided upon the car for tripping said switch. Fig. 3 is a central longitudinal section of the switch. Fig. 4 is a detailed fragmentary section of the switch locking means, and Fig. 5 is a section on the line 5—5 of Fig. 4.

Referring specifically to the accompanying drawings the numeral 1 designates a main track and the numerals 2 and 3 designate curved tracks extending into opposite direction and designed to be individually merged with the track 1 by the mechanism provided therefor and forming the present invention. Adjacent the junction of the tracks 1, 2 and 3 is an annulus 4 having a horizontal flanged extension 5 by which said annulus is secured to the road bed. The annulus 4 serves as a positive support for the switch mechanism. The latter comprises a disk shaped plate 6 formed with a depending flange 7 which rests upon the annulus 4, said flange being provided with an off-set depending shoulder 8 surrounding the outer side of said annulus and serving to prevent the lateral displacement of the plate 6. Owing to its loose manner of assemblage the plate 6 is freely rotatable upon the annulus 4 and is provided with track sections 2^a and 3^a oppositely curved and serving to merge the track 1 with the re-

spective tracks 2, and 3. Between the sections 2^a and 3^a is a vertically extending post 9 projecting thereabove, which affords an obstacle designed to be engaged by suitable means provided on the car in rotating the plate 6.

As above intimated the rotation of the plate 6 is a partial one and to this end the annulus 4 is provided with stationary inward projections 10 which afford stops to prevent the rotation of the plate 6 at selected points and are engaged in this function by depending projections 11 carried upon said plate and arranged on opposite sides of the adjacent stop 10 so that one projection 11 will engage the adjacent stop when the plate 6 is rotated in one direction and the other projection will engage the stop adjacent thereto when the plate 6 is rotated in an opposite direction. The projections 10 and 11 are shown in dotted lines in Fig. 1. For the purpose of preventing the accidental displacement of said plate from any position to which it may be moved, the annulus 4 is provided with an inwardly projecting portion 12 having depressions 13 and 14 arranged in the upper edge thereof. The depressions 13 and 14 are formed with inclined sides which afford cam surfaces for a depending shoe 15 provided upon the plate 6. Said depressions 13 and 14 are spaced apart a distance equal to the complete rotative movement of said plate and as shown in Fig. 4 the shoe 15 is engaged in the depression 13. It is obvious that when said plate 6 is rotated in the opposite direction, said shoe will ride out of said depression upon the cam surface thereof and will engage in the depression 14. This engagement is of course effected by the weight of the plate 6 and it is to be noted that the shoe 15 has its lower edge conformable to the depressions 13 and 14.

In Fig. 2 an advantageous embodiment of means for rotating the plate 6, in the manner described, is illustrated. Such means comprises a vertical shaft 16 journaled in the floor 17 of the car and loosely held by means of a stop 18 provided on said shaft. The upper end of said shaft is provided with an operating handle 19 and the lower end with an enlarged tripping head 20. Adjacent to the shaft 16 is a curved block 21 which is formed in its lower portion with a horizontal recess (not shown) for the reception of a projection 22 carried by said shaft, said recess serving to guide said shaft and to maintain the same in

operative position against displacement by obstacles. The upper part of the block 21 is cut away so as to afford a retaining wall for the projections 22 as indicated in dotted lines, 5 when the shaft 16 is lifted to lift the head 20 out of the path of the post 9. Said shaft is lifted by simply rotating the same until the projection 22 moves out of the recesses therefor in the block 21 and by then lifting said 10 shaft until said projection can be placed upon the upper surface of said block.

It is often times necessary for the purpose of repairs that the plate 6 be removed from the annulus 4. To this end a suitable handle 23 15 of approved form is provided, said handle being arranged centrally of said plate as is illustrated in Fig. 1.

While the elements herein shown and described are well adapted to serve the functions set forth, it is obvious that various 20

minor changes may be made in the proportions, shape and arrangement of the several parts without departing from the spirit and scope of the invention.

Having fully described my invention I 25 claim:

A switch comprising a stationary annulus, a plate movable thereon, a projection on said annulus having spaced depressions therein, a projection on said plate designed for engagement in said several depressions, means for partially rotating said plate, and means for limiting the movement of said plate in either direction. 30

In testimony whereof I affix my signature 35 in presence of two witnesses.

MALCOLM C. MATTHEWS.
